(57) **CLAIM**

The ornamental design for a charger, as shown and described.

DESCRIPTION

FIG. 1 is a top perspective view of a charger according to the first embodiment of the present design.

FIG. 2 is a bottom perspective view of the charger of FIG. 1.

FIG. 3 is a front view of the charger of FIG. 1.

FIG. 4 is a back view of the charger of FIG. 1.

FIG. 5 is a left side view of the charger of FIG. 1.

FIG. 6 is a right side view of the charger of FIG. 1.

FIG. 7 is a top view of the charger of FIG. 1.

FIG. 8 is a bottom view of the charger of FIG. 1.

FIG. 9 is a top perspective view of a charger according to a second embodiment of the present design.

FIG. 10 is a bottom perspective view of the charger of FIG. 9.

FIG. 11 is a front view of the charger of FIG. 9.

FIG. 12 is a back view of the charger of FIG. 9.

FIG. 13 is a left side view of the charger of FIG. 9.

FIG. 14 is a right side view of the charger of FIG. 9.

FIG. 15 is a top view of the charger of FIG. 9; and,

FIG. 16 is a bottom view of the charger of FIG. 9.

The broken lines in the drawings are for the purpose of illustrating portions of the charger that form no part of the claimed design.

1 Claim, 16 Drawing Sheets
